UNITED STATES PATENT OFFICE

WILLIAM EVANS KEHOE, OF SAN FRANCISCO, CALIFORNIA

DESIGN FOR A DISPLAY DRESS AND COAT HANGER

Application filed August 26, 1929. Serial No. 32,539. Term of patent 14 years.

To all whom it may concern:

Be it known that I, WILLIAM EVANS KEHOE, a citizen of the United States, residing at the city and county of San Francisco, State of California, have invented a new, original, and ornamental Design for a Display Dress and Coat Hanger, of which the following is a specification, reference being had to the accompanying drawing, forming part thereof.

I claim:

The ornamental design for a display dress and coat hanger as shown.

WILLIAM EVANS KEHOE.
